UNITED STATES PATENT OFFICE.

GEORGE C. BLICKENSDERFER AND HERVEY SMITH, OF ERIE, PA.

CONVEYER APPARATUS.

SPECIFICATION forming part of Letters Patent No. 298,276, dated May 6, 1884.

Application filed March 23, 1884. (No model.)

To all whom it may concern:

Be it known that we, GEORGE C. BLICKENSDERFER and HERVEY SMITH, citizens of the United States, residing at Erie, in the county 5 of Erie and State of Pennsylvania, have invented certain new and useful Improvements in Conveyer Apparatus; and we do hereby declare the following to be a full, clear, and exact description of the invention, such as will 10 enable others skilled in the art to which it appertains to make and use the same.

This invention relates to that class of conveyers wherein the track consists of a single taut wire, or of bars sustained by brackets; and 15 the car consists of one or more flanged wheels and means for suspending the load below the track.

The invention consists in providing such a conveyer apparatus with an automatic switch 20 which is set to receive the car, and after the car is received is unset or thrown back by the movement of the car itself.

We are aware that automatic switches have been used on surface railroads having two lines 25 of track, but are not aware that they have ever been used in conveyers of the class above named.

In four patents issued to us March 18, 1884, we have shown various forms of automatic 30 switches for conveyers of this class; but they are all fixed or non-moving switches, and the cars are provided with a separate set of wheels for use on the switches. In this application we show such a conveyer with a car having 35 only a single running-gear, which runs on both the main line and the switches, and the switch-points are movable, and are thrown into and out of connection with the main line by the movement of the car. We show our invention 40 applied to tracks formed of taut wire and of bars, and we show two optional constructions, both of which, while dissimilar in the details of construction, are substantially alike in general features, and each embodies the 45 essential principles of our invention.

Our invention appears in the accompanying drawings, as follows:

Figure 1 is a perspective view of a receiving-station on a conveyer-line. Fig. 2 is a 50 similar view showing an alternative construction.

In each figure the track is shown by full

lines to be of taut wire, and by dash and dot lines to be of bars. The difference in the two constructions is as follows: In Fig. 1 a section 55 of the main line is made movable, and the point of the switch takes its place when the switch is set to receive a car. In Fig. 2 the main track remains intact, and the point of the switch, when in position to receive the 60 car, lies upon the main track, and, being inclined, lifts the car-wheels up, so their flanges will pass over the main track.

The various parts are indicated by letters of reference, as follows:

A is the main track.

B is the switch or branch track.

B' and B² are the swinging switch-points.

A' A' is the swinging section of the main track.

A² is an iron which deflects the wire forming the main line, and forms a seat for the swinging section A'.

C C' C² C² is the gearing by which the switch is moved before the car reaches the 75 switch.

F F' F² is the gearing by which the car moves the switch after it has received the car.

E E' are hangers which support the main and branch tracks.

E² E' is a frame-work which supports an arc-shaped track, D'.

D d d is a car mounted on said arc-track, and carries hangers D² D², which support the movable sections A' and B', or in Fig. 2 the 85 movable section B². The car or slide D d d is moved by the gearing C C', &c., or F F', &c., as the case may be. The car is shown in Fig. 1 by dotted lines.

The position of parts in both figures is that 90 which they assume when the switch is set to receive a car—that is to say, the position they are thrown into by the car as it passes the lever C, in which position the car is shown by dotted lines.

The levers C at different stations are of different lengths, and a pin on the side of the car-standard is placed in proper position to hit the end of the lever C only at the station to which that car is destined, and to pass all other 100 such levers on the line without hitting them. The levers F, which the car hits to close the switch behind it—that is, to move the switch out of connection with the main track—may all

be of the same length, and are set so as to be struck by the upright of the car-frame.

When the tracks are made of bars, as indicated by dash and dotted lines, the casting or 5 deflecting seat-iron A² is not used, the bar being notched to receive the swinging section A'. The iron A² is only wanted when the track is of taut wire and such a switch as is shown in Fig. 1 is used. It is not wanted for such a 10 switch as is shown in Fig. 2 when the track is a taut wire. Its chief office is to deflect the wire, so as to form a notch or offset to receive the swinging section A' and to form a seat for that section.

15 The switch-point or swinging section B² in Fig. 2, when in position, as shown, to receive the car, lies directly upon the main line and grades up from its point high enough to raise the wheel-flanges above the main line before 20 it curves off to one side, so that the car will have to run up a slight incline, and will then run off on the switch and its wheel-flanges will clear the main line.

The operation is as follows: Before the car 25 passes the lever C the switch-point is off from the main line and the main line is open for the free passage of cars that are set to not hit the lever C. When the car hits the lever C, it moves it forward and the rod C' turns the 30 bell-crank C² C³ C⁴, and the pin d' on the car or slide D being in the slot e on the arm C⁴, the car is moved back, and this, by reason of its connection with the switches through the 35 hangers D² D³, carries the said switches into the position in which they are shown, which is such as to cause the car to run off on the switch. As the car passes the lever F it moves it, and as the parts F F' F² form a bell-crank with the arm F², connected with the 40 movable switch-point, this movement will throw the switches and the car D, and also the gearing C, &c., back into the position they occupied before the car came in contact with the lever C. It will thus be seen that the whole 45 movement of the switch is automatically effected by the movement of the car.

What we claim as new is—

1. In a conveyer apparatus substantially as shown, the combination of the following 50 elements: an elevated track, a swinging-switch track, a pendent car, and gearing for swinging said switch, which is actuated by coming in contact with the said car as it passes, substantially as shown.

2. In a conveyer apparatus substantially 55 as shown, the combination of the following elements: an elevated track, a swinging-switch track, the arc-track D', the slide or car D, a hanger connecting said slide or car with the swinging switch, gearing, substantially as shown, for moving said slide from the levers C and F, and a pendent car having means, substantially as shown, for moving said levers C and F as it passes them.

3. In a conveyer apparatus substantially 65 as shown, the combination of the following elements: an elevated track with an offset or notch and a swinging section in said notch, a swinging-switch track, an arc-track, a sliding hanger mounted on said arc-track, and supporting said swinging-switch and main-track section, gearing, substantially as shown, for moving said sliding hanger from the levers C and F, and a pendent car with means, substantially as shown, for moving said levers C 70 and F as it passes them.

4. In a conveyer apparatus substantially 75 as shown, the combination of the following elements: an elevated main track, a pendent car, and a swinging switch which is actuated from the movement of the car.

5. In a conveyer apparatus substantially 80 as shown, the combination of the following elements: an elevated main track, a pendent car, and a swinging switch and swing section of main track which are actuated from the movement of the car.

6. In a conveyer apparatus substantially 85 as shown, the combination of the following elements: an elevated main track having a 90 swinging section, a swinging switch lying opposite said swing track section, and means, substantially as shown, for moving said two swing parts simultaneously from the action of the passing car.

7. In a conveyer apparatus substantially 95 as shown, the combination, with a taut-wire main track, of the deflecting-iron A², the swinging-track section A', and the swinging switch B'.

In testimony whereof we affix our signatures in presence of two witnesses.

GEORGE C. BLICKENSDERFER.
HERVEY SMITH.
